PLINY E. HOLT, OF STOCKTON, CALIFORNIA.

TRACTION-BELT FOR TRACTORS.

1,111,583.

Specification of Letters Patent. Patented Sept. 22, 1914.

Application filed February 26, 1912. Serial No. 680,078.

To all whom it may concern:

Be it known that I, PLINY E. HOLT, a citizen of the United States, residing at 820 West Poplar street, in the city of Stockton, county of San Joaquin and State of California, have invented certain new and useful Improvements in Traction-Belts for Tractors; and I do hereby declare the following to be a full, clear, and exact description of the 5 said invention, such as will enable others skilled in the art to which it most nearly appertains to make, use, and practise the same.

This invention relates to improvements in tractors of the "caterpillar" type, and relates more particularly, to and consists of the novel construction and arrangement of the traction sections forming the traction belt.

The objects sought to be accomplished are 20 to minimize the number of parts, and transmit the tractive and supporting burden directly to the traction shoe; to overlap the adjacent ends of the traction shoes to form wipe joints to prevent the incursion of mud 25 and dirt between the track sections; and to provide, against the accumulation of mud and dirt in the link sections; and to provide means for suitably lubricating the articulations of the traction belt or track.

Particular stress is laid upon the value of 30 the open gridlike construction of the link sides. The worst enemy of this type of traction belt is grit and mud accumulations within and about the link sections; especially if the mud is permitted to harden between the gudgeon blocks within the links. The open sided links of the present invention prevent the disrupting effect consequent upon compression of such obstructions by 40 the driving sprocket teeth entering into each successive link. The side openings permit of the lateral dislodgment of dirt, mud, gravel or other foreign matter.

Broadly the invention consists of a series 45 of traction shoes having upturned edges and depressed grousers, and end extensions overlapping the ends of the adjacent traction shoes; link sides of open gridlike construction, with profile lugs engaging the depressed grousers and bolted to the traction 50 shoes, and joined by gudgeon blocks having an oil font therein and gudgeon pins to form a self lubricating articulation between the traction sections.

In the drawings: Figure 1 is a side elevation 55 illustrating a traction belt constructed

in accordance with this invention. Fig. 2 is a plan view detail from above of the same. Fig. 3 is a side elevation of the same. Fig. 4 is a side elevation detail of the gudgeon 60 block. Fig. 5 is an end view of the same.

In detail the construction consists of the traction shoe 1, having the upturned edges 2, the curved overlapping ends 3 and 4, and the depressed grousers 5 upset from the 65 body of the shoe, extending transversely of the same.

The draft chain consists of the link sides 6 and 7 having the profile lugs 8 adapted to follow the inner contour of the traction shoe, 70 to which they are fixed by the bolts 9 extending through the ears 10. The supporting track 11 is formed integral with the link sides, and is adapted to support the rollers X of the tractor truck a sufficient height 75 from the ground to avoid mud and grit, accumulations of which are ejected through the openings 12 in the link sides. The companion links are joined to the succeeding series by the gudgeon blocks 13 extending between the link sides of the narrow 80 end of the link, which is let into the wide end of the succeeding link to form a break joint in the supporting track. The gudgeon pins 14 extend through the gudgeon blocks 85 and the interlocked ends of the draft links, wherein they are secured by the transverse taper pins 15 driven therethrough and clenched. The gudgeon pins are prevented from rotating by the lugs 16 formed on the 90 link sides and engaging the transverse pins.

The gudgeon blocks have cylindrical body portions, adapted to engage the driving sprocket Z, and the reduced ends 18 flattened to engage the similarly shaped holes 19 in the ends of the link sides. The oil font 20 is formed integrally with the gudgeon block and has a cored opening into the center bore 21. The font is filled with oil before the gudgeon pins are inserted, the 100 oil is distributed whenever the traction belt assumes the inverted position in passing around the driving sprockets.

The two link sides with the gudgeon blocks and pins form an endless series of 105 draft links adapted to be engaged by the driving sprocket Z, which pulls the traction sections progressively under the supporting truck rollers, which roll upon the track sections imparting progressive motion to the 110 tractor. The grousers engaging the ground prevent slipping of the traction belt. The

overlapping ends 3 and 4 form a wiping joint permitting free articulation of the link sections; but prevent mud or soft earth from squeezing up between the sections and causing undue deterioration of the wearing parts.

It will be noted that the track belt is formed by a series of articulated sections, each section embodying a shoe having 10 grouser projections on its outer face and corresponding recesses on its inner face and links which at the ends are provided with joint connections for articulation, at their inner edges with substantially straight 15 track bearings for the truck wheels, and at their outer edges with projections which seat in the recesses in the shoes, whereby any 20 tendency of the shoes to slide with relation to the links is overcome, and the holding 25 bolts have therefore only to bear the strains tending to radially separate the parts. Each link is provided with side openings, which openings extend beyond the plane of the joints and cross pieces with which the 30 teeth on the drive sprocket coöperate, whereby the sprocket teeth entering the spaces between the cross pieces or joints will force any accumulations out through the lateral 35 openings. The drive wheel operates with its periphery between the track heads of the 40 links, and it is of importance in such a structure that lateral openings be provided inasmuch as the accumulations of mud and dirt would not otherwise be afforded an opportunity to escape, a result which is incident, so far as known, to the structure of the 45 present application alone.

Having thus described this invention what is claimed and desired to secure by Letters 50 Patent is:

1. A traction belt for tractors formed by a series of articulated link sections, each section embodying a transversely corrugated shoe plate and a link with joint connections for articulations at its ends, said track link having a rail head portion along one of its longer sides, the opposite side of the track link being bolted to the shoe plate and having lugs seating in the corrugations in the shoe and coacting with the bolt to hold the shoe rigidly in place, substantially as described.

2. A traction belt for tractors, formed by a series of parallel articulated links having 55 sprocket wheel engaging portions extending transversely thereof, and lateral openings in the links for the escape of accumulations at points beyond or on the outer side of the plane of the sprocket wheel engaging portions of the links, whereby the entry of the sprocket teeth between the links 60 will expel accumulations laterally from the links.

3. A traction belt for tractors, formed by 65 a series of parallel articulated link sections

having truck supporting rail faces on their inner edges and transversely extending sprocket wheel engaging portions at their ends with lateral apertures extending beyond the plane of the sprocket wheel engaging portions, and shoes bridging the space between the links at their outer sides.

4. A traction belt for tractors comprising a series of articulated links having a gudgeon block with an oil font therein, 75 and a gudgeon pin engaging the interlocked link ends; transverse pins engaging the ends of the gudgeon pins and lugs formed on the link sides; a series of overlapping track shoes having depressions adapted to engage lugs formed on the link sides.

5. In a belt for a self-laying track, the combination of a shoe plate with a pair of transverse indentations on its inner side, a link section having a substantially straight rail-head on one edge and an undulating opposite edge to fit the indentations in the shoe, and a bolt passing through the shoe plate and through an offset portion of the link section, said bolt and said lugs and 90 indentations coöperating to hold the plate and link rigidly against relative movement.

6. In a traction belt mechanism for tractors of the type described, the combination with a belt formed by a series of articulated 95 link sections, each section embodying a shoe plate and spaced parallel track links secured to the shoe plate, said track links having pivotal connections at the ends, lateral openings in the links between said 100 pivotal connections and extending outwardly beyond the same, and substantially straight track rail heads on the inner edges of said track links, of truck wheels traveling on said rail heads, and a driving 105 sprocket wheel traveling between the side link sections and having teeth projecting 110 into the spaces between the transverse pivotal connections, whereby accumulations entering the belt in proximity to the truck wheels will be forced laterally through the openings in the links by the entry of the driving wheel.

7. A track belt for tractors comprising an endless series of articulated sections, each section being formed by grouser plates having external projections and corresponding internal depressions and curved end extensions and side links to which said grouser plates are secured having edge profile projections seating in the depressions in the plate and end extensions to overlap corresponding extensions of adjacent sections and gudgeon blocks and pivot pins forming the axes between adjacent side links.

8. A track belt for tractors comprising an endless series of articulated sections formed of links having overlapping joint track portions on their upper edges and profile lugs on their lower edges, and grouser 130

- plates secured on said links and having depressions in which the projections seat, adjacent grouser plates having curved overlapping ends forming wipe joints to exclude dirt.
5. 9. A traction belt for tractors, comprising an endless series of articulated duplicate sections, each section embodying a grouser plate and track link, proximate links having their ends overlapping and pivotally connected, the proximate grouser plates having overlapping curved ends one outside of the other radially of the axis, the curvature of said overlapping portions being approximately concentric with the axis and being extended in opposite directions beyond a plane radial to the axis at right angles to the plane of the sections when straight and being co-extensive in width with the bodies of the plates to form a wiping joint and a substantially unbroken surface to exclude dirt and support the weight of the tractor.
10. 10. A track belt for tractors formed of an endless series of duplicate short articulated sections, each section embodying a track forming link and a grouser plate independent of but rigidly attached to the link and having its front and rear ends extended beyond planes at right angles to the plane of the plate and radial to the axes of articulation to overlap corresponding extensions on adjacent plates, said over-

lapping portions of the plates having contacting faces substantially concentric with the axes of articulation and substantially the width of the body of the plates, whereby the plates mutually support each other at all times, and a continuous bearing between the sections exists at all times to prevent the entry of dirt.

11. A track belt for power driven tractors formed of an endless series of duplicate short articulated sections each section embodying a track forming link having rounded end portions and a grouser plate independent of but rigidly attached to the link, and having roadway engaging projections on its outer face and its front and rear ends extended beyond planes at right angles to the plane of the plate and radial to the axes of articulation to overlap corresponding extensions on adjacent plates, said overlapping portions of the plates having contacting faces substantially concentric with the axis of articulation and lying on the inner side of the plane of the projections whereby a continuous bearing surface will be formed between the sections and the entry of dirt will be prevented.

In testimony whereof, I have hereunto set my hand this 25th day of January 1912.
